Filed Aug. 26, 1968, Ser. No. 13,266

Term of patent 3½ years

Int. Cl. D26—06

U.S. Cl. D48—16

FIG. 1

FIG. 2

FIG. 1 is an elevational view of the lamp shade showing my design;

FIG. 2 is a top plan view thereof.

In FIG. 1 the four immediately facing panels on the skirt of the lamp constitute one of three repeat units surrounding the annular skirt.

I claim:

The ornamental design for a lamp shade, as shown and described.
